UNITED STATES PATENT OFFICE.

ANTHONY McF. McSWEENEY, OF SALT LAKE CITY, UTAH.

SKIRMISH-MACHINE.

1,002,169.

Specification of Letters Patent. Patented Aug. 29, 1911.

Application filed July 8, 1910. Serial No. 570,929.

To all whom it may concern:

Be it known that I, ANTHONY McF. McSWEENEY, a citizen of the United States, residing at Salt Lake City, in the county of 5 Salt Lake and State of Utah, have invented a new and useful Skirmish-Machine, of which the following is a specification.

The present invention provides an engine of warfare which is self-propelling and 10 armored so as to amply protect the vital parts and the complement of men manning the same. The machine besides being self-propelling, so as to move from place to place by its own power, is adapted for use as a 15 traction engine for drawing ordnance, wagons, or vehicles containing supplies or munitions of war.

The invention contemplates the provision of a machine of the character aforesaid 20 which may be used for protecting the rear of coast defenses, bridges or other structures, or which may be employed to protect detachments when making advances or for other purposes requiring protection against 25 opposing forces or which may be used on the offensive as well as the defensive.

The invention consists of the novel features, details of construction and combination of parts, which hereinafter will be 30 more particularly set forth, illustrated in the accompanying drawings, and pointed out in the appended claims.

Referring to the drawings, forming a part of the application, Figure 1 is a side view 35 of a machine embodying the invention. Fig. 2 is a vertical central longitudinal section thereof. Fig. 3 is a horizontal section of the machine on the line 3—3 of Fig. 2. Fig. 4 is a front view. Fig. 5 is a rear view 40 of the machine.

Corresponding and like parts are referred to in the following description, and indicated in all the views of the drawings, by the same reference characters.

The machine comprises a shell or hollow body of peculiar formation so as to afford 45 protection alike for the machinery, armament and men manning and operating the same, said body being constructed of plate 50 steel of suitable thickness according to location and the degree of resistance to be afforded to penetration. The body of the machine is mounted upon front wheels 1 and rear wheels 2, said wheels being of substantial construction and armored in a way 55 to protect them from injury or the penetra-

tion of missiles that may come in contact therewith. The wheels are also supplied with yieldable tires, which are protected by suitable armor to prevent missiles 60 disabling the same. The front wheels 1 are mounted to admit of properly steering the machine and are moved from the interior of the body by means of the operator in the manner well understood in the manipulation of automobiles. The rear wheels 2 are utilized as drivers for propelling the machine. The engine 3 may be of any type and horsepower according to the work required thereof. Any means may be employed for transmitting power from the engine to the drive wheels and as indicated 65 drive chains and sprocket chains are employed. The engine 3 is located at the front of the machine and is arranged in a 70 separate compartment 4 through which a current of air is circulated so as to cool the engine and carry off the hot air, the cool air entering inlets 5 at the front of the shell or body and passing out at 6 in the rear of the compartment 4. The compartment 7 in the rear of the engine compartment 4 is 75 adapted to receive the armament, the operator and the men manning the machine. The compartment 7 has a seat 8 for the operator and other seats 9 for the men or persons manning the machine. Lockers 10 are arranged along opposite sides of the body for receiving ammunition, small munitions and sundry articles. A series of trap doors 11 close openings formed in the bottom of the body and may be used as convenient means for ready ingress and egress for adjustment of machinery without exposing the persons to direct danger. A 80 platform 12 is located in the rear and doors 13 afford ingress and egress in the rear from the platform. The front of the body has a prow 14, which tapers laterally and upwardly and downwardly, the forward 85 end being pointed. This prow enables the machine to ward off obstructions in its path and in the event of cables or analogous devices being placed across roadways the prow rides under or over said obstructions, thereby enabling the machine to clear the same. The inlets 5 are formed in the under walls 90 of the prow and are thereby positioned so as to prevent ready access of missiles into the shell or body. The upper portion 15 of the body is made rounding transversely and forwardly and downwardly inclined 95 100 105 110

and has a tapered portion 16 between its front end and the rear portion of the upper walls of the prow 14. The sloping formation of the parts 15 and 16 enables the same 5 to ward off missiles as well as to ride under obstructions which are deflected upwardly by the prow 14. The body tapers as a whole from rear to front, the purpose being to present inclined walls which will serve to 10 deflect missiles and obstructions. The upper portion of the body above the compartment 7 has a raised portion 17, the sides of which are forwardly converged and the top of which inclines forwardly and rear- 15 wardly and curves laterally, the walls presenting deflecting planes so as to shed or ward off missiles that may come in contact therewith, the inside of walls 17 being vertical from floor to roof. An observation 20 opening 18 is formed in the front portion of the raised part 17 and this opening is adapted to be closed by means of slides 19, which are operable by means of rack and pinions arranged within convenient reach 25 of the operator's seat 8. A nose bridge 20 is located in advance of the raised part 17 and serves to direct any obstruction passing over the part 15 upwardly to the top or roof of the part 17. 30 Small arms are located upon the walls of the shell or body in position for instant use when required. Turrets 21 are located upon opposite sides of the shell or body, preferably near the rear thereof and the vertical 35 or outer walls of such turrets have horizontal slots 22 through which project machine guns 23, the latter being mounted to sweep in a circle so as to point to any angle from front to rear. The shell or body is completely inclosed at its top, bottom and sides 40 and the means for transmitting power from the engine to the drive wheels are also housed or inclosed to protect them from injury. Search lights 24 are located near the front of the machine upon opposite sides of the raised portion 15 and are adapted to be 45 protected by plates 25, which may be arranged to be moved aside so as to uncover the search lights when observations are to 50 be made in dark places or after nightfall.

Various openings in the shell or body are sufficient for ventilation and by locating the engine in a compartment separate from that designed to receive the operator and persons 55 manning the machine prevents overheating of the compartment 7 and the filling of the same with gases and obnoxious odors. Moreover, said compartment 4 may be cooled by circulating air therethrough, thereby preventing overheating of the engine, it being understood that fans or other means may be employed for creating a positive circulation of air.

The machine is self-propelling and as 60 hereinbefore stated may be used either to

act as a convoy to a supply train or to draw vehicles containing munitions and supplies of war. The machine guns or rifles 23 may be used to advantage at long range and in close quarters the small arms forming a complement of the armament may be advantageously used. The hollow body or shell by reason of its substantial structure serves as a protection to enable a comparatively small force to hold out against a larger force 75 until assistance may be had. The advantages of a machine of the character set forth are readily understood both when the machine is used on the offensive or defensive.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the embodiment thereof, I desire to have it understood that the device shown is merely illustrative, and that such changes may be made when desired as are within the scope of the claims appended hereto.

Having thus described the invention what is claimed as new, is:—

1. A skirmish machine comprising a hollow body, or shell, formed of inclosing walls of plate steel and tapering from front to rear and having a tapered prow and front and rear raised portions, each of the raised portions having its side walls forwardly converged and its top sloping and said body having a tapered portion between the prow and the front raised portion.

2. A skirmish machine comprising a hollow body or shell mounted upon wheels and embodying an engine for propelling the machine, said body having a raised portion and having turrets at the sides of the raised portion, said turrets being adapted to receive machine guns and having horizontal slots through which the guns may project and are adapted to sweep in a range from front to rear.

3. A skirmish machine comprising a hollow body mounted upon wheels and embodying an engine for propelling the machine, said body being subdivided into front and rear compartments, the front compartment receiving the engine and having cool air inlets and hot air outlets and the rear compartment being adapted to receive the operator and men manning the machine and the controlling devices and the armament, said rear compartment having a raised portion and the latter having turrets at its sides to receive machine guns or rifles, said turrets having horizontal slots to admit of the machine guns having a sweep or range of movement from front to rear.

4. A skirmish machine comprising a hollow body or shell formed of inclosing walls of plate metal and having said walls sloped or inclined to provide a plurality of deflecting surfaces for warding off missiles and obstructions, said body having a pointed prow at the front, a raised portion in the rear of said prow and an elevated portion at the rear, and having an observation opening formed in the front of the rear elevated portion, and a nose bridge between the front of said rear elevated portion and the rear of the forward elevated portion.

5. A skirmish machine comprising a hollow body or shell formed of inclosing walls of plate metal and having said walls sloped or inclined to provide a plurality of deflecting surfaces for warding off missiles and obstructions, said body having a pointed

ed prow at the front, a raised portion in the rear of said prow and an elevated portion at the rear and having an observation opening formed in the front of the rear elevated portion, a nose bridge between the front of said rear elevated portion and the rear of the forward elevated portion, and turrets upon opposite sides of the rear elevated portion formed with slots through which rifles project and are adapted to be pointed to any angle within the range of movement from front to rear.

In testimony whereof I affix my signature in presence of two witnesses.

ANTHONY McF. McSWEENEY.
